UNITED STATES PATENT OFFICE.

PETER GOOD AND ADAM GOOD, OF WILKES-BARRÉ, PENNSYLVANIA.

DESIGN FOR AN OIL-CAN.

SPECIFICATION forming part of Design No. 22,489, dated May 30, 1893.

Application filed April 26, 1893. Serial No. 471,990. Term of patent 14 years.

To all whom it may concern:

Be it known that we, PETER GOOD and ADAM GOOD, citizens of the United States, residing at Wilkes-Barré, in the county of Luzerne and State of Pennsylvania, have invented and produced a new and original Design in Oil-Cans, of which the following is a specification, reference being had to the accompanying drawing, in which we show a side view of the can complete.

The leading feature of our design consists in a body cone-shaped, somewhat modified, one side being substantially vertical and its opposite side oblique, together with a cylindrical handle rising from a point near the base of the vertical side and being substantially parallel with the opposite side, and a

cylinder substantially the same size as the handle issuing from a point near the top of the handle and terminating upon the vertical side of the body, thereby preserving and giving the oil-can a general appearance of symmetry.

Having described our invention, what we claim is—

The design for a can, substantially as herein described and shown.

In witness whereof we have hereunto set our hands this 19th day of April, 1893.

PETER GOOD.
ADAM GOOD.

In presence of—

A. BARBER,
L. BARBER.
